UNITED STATES PATENT OFFICE.

REUBEN H. CHASE, OF BOSTON, MASSACHUSETTS.

DEVICE FOR SUPPORTING AND DELIVERING PAPER FOR WRAPPING OR BUNDLING PURPOSES.

No. 830,206.

Specification of Letters Patent.

Patented Sept. 4, 1906.

Application filed December 14, 1904. Serial No. 236,800.

To all whom it may concern:

Be it known that I, REUBEN H. CHASE, a citizen of the United States, residing at Boston, in the county of Suffolk and State of Massachusetts, have invented an Improvement in Devices for Supporting and Delivering Paper for Wrapping or Bundling Purposes, of which the following description, in connection with the accompanying drawings, is a specification, like characters on the drawings representing like parts.

This invention has for its object the production of an improved apparatus by which to deliver a gummed strip in any desired length to be used for wrapping bundles, the strip being employed instead of usual string or india-rubber bands.

The particular features of which my invention consists will be hereinafter described, and fully pointed out in the claims at the end of this specification.

Figure 1 is side elevation, the liquid-containing box being in section, illustrates an apparatus embodying my invention. Fig. 2 is a somewhat enlarged section of the moistening means, and Fig. 3 shows the end of one of the tie-rods.

Referring to the drawings, A represents a base-plate or bed, to which is secured a standard A' of any suitable shape, that supports a casing A², the standard having a central stud that receives over it a roll of paper B, preferably on a wooden spool B'. The stud is of sufficient length to receive a plurality of spools, each spool containing, it may be, a gummed strip of paper of a definite width, the width of the two strips varying.

When a plurality of rolls of paper are used, I separate the rolls by means of a disk a also sustained by the stud and I apply a second disk a' to the outer side of the outermost roll of paper, securing the same by means of a thumb-nut a² or otherwise. The casing has a mouth a³, through which the gummed strip is led to the moistening device, to be described. The rotation of the disks a and a' is restrained by means of a disk-locking device a⁴.

At or near the end of the base I erect suitable standards for sustaining the moistening means. The standards herein shown comprise two side plates C, represented as flanged outwardly at their lower ends and connected to the base by screws C'. The side plates are connected rigidly by means of tie-rods 2, 3, 4, and 5. These tie-rods consist of pieces of

metal shouldered at or near one end, as at c, Fig. 3, and threaded to receive suitable nuts 6, the shoulders of the rods abutting the inner sides of the standards, as shown.

6c

Above the tie-rod 2 I have mounted a strip-sustaining rod 7, it being provided, as represented, with a loose washer adjustable longitudinally thereon, so that it may be moved on the rod at any desired distance 65 from its end to thus accommodate a plurality of strips, the contiguous edges of the strips abutting the sides of the washer. The gummed strip, with its gummed side uppermost, is led over the rod 7 behind or to the left of the rod 2, thence across the rod 3 and under a roller 8. The rod 3 is so located with relation to the rod 2 and roller 8 that the gummed and stiffened strip is bent as it travels between the rod 2 and roller 8, and this bend serves to give the strip a tendency 70 to drop upon the rod 4, and, further, the rod 3, when the strip is released after the same has been cut off, prevents the movement of the strip too far to the left, viewing Fig. 2, and 75 the rod 2 at the other side of the strip prevents the approach of the strip toward the moistening device when the strip is cut off. The free end of the strip normally drops on the tie-rod 4, which constitutes a strip-sup- 85 port for the strip back of its free end.

The bed at its end and at one side of the stand referred to has secured thereto a strip-cutter D, shown as a toothed piece of metal, which is herein represented as secured to the 90 bed by some of the screws employed for securing the standard to the bed. The upper ends of the standards have connected to them by screws 10 and 12 the part of the bottom plate d of the tank d' which contains the 95 water to be delivered to the fibrous covering d^x of the moistening device.

The interior of the box has a tube d² that receives the stem of what I shall designate a "needle-valve" d³, it having a threaded shank and a tapering point, the rotation of the stem leaving more or less space about the tapering point to control the amount of water to drop through the tube onto a sponge f, which is deposited in a U-shaped trough d⁴, 105 forming the body of the moistening device. The body of the moistening device at its lower side has a series of fine holes h, so that the water which is permitted to drop through the needle-valve onto the sponge may be 110 given up slowly and flow through said holes and enter the fibrous covering d^x applied to

the exterior of the body of the moistening device. The fibrous material is clamped to the body of the moistening device by cleats 14, held by screws 15. The upper part of the 5 body of the moistening device is represented as having out-flaring lips 16 that enter guide-ways formed at the under side of the tank, so that the moistening device may be with- drawn from the apparatus whenever it is de- 10 sired. The upper end of the needle-valve is extended through the tank-cover d^e and is readily accessible to the hand of the user, and the cover may be raised whenever it is de- sired to supply water to the tank.

15 Fig. 1, in full lines, shows the apparatus in its normal condition. A clerk or other per- son being desirous of wrapping a bundle will engage the free end of the gummed paper and will push the same backwardly a little, as in- 20 dicated by dotted lines, Fig. 1, and will then raise the strip, putting the gummed side thereof close to the point where the thumb and forefinger are holding the strip against the moistened under side of the fibrous cov- 25 ering of the moistening device and will pull the strip upwardly in the direction of the dotted line 20, pulling off more or less of the strip according to the size of the bundle to be wrapped, and when the strip has been pulled 30 off for the desired length the clerk will drop the same into the dotted-line position 21 and will cut off the strip by the lower knife. In some instances, however, it will be desirable to cut off the strip by an upward movement, 35 and in such event I have provided the top of the stand with a second or auxiliary cutting-plate e , shown as a saw-toothed piece of metal held in position by screws 12.

Prior to my invention I am not aware that 40 a gummed strip has ever been drawn from a roll underneath a moistening device to moisten the gummed side of the strip and there-

after cut off the strip. When the strip is cut off by the lowermost cutting device, the dry end of the strip remains in position on the 45 strip - sustaining rod 4. If, however, the strip is cut off by an upward movement, then the strip immediately drops on said rod, due to its weight and gravity.

Having fully described my invention, what 50 I claim as new, and desire to secure by Letters Patent, is—

1. In apparatus of the class described, a tank, a moistening device located below said tank, a plurality of rods between and over 55 which to draw a strip on its way to be acted upon by the moistening device, means for cutting off the moistened strip, and a device to sustain the end of the strip below and out of contact with the moistening device. 60
2. In apparatus of the class described, a tank, a moistening device therebelow having an exterior fibrous covering, rods over which the strip to be moistened is drawn, and means for cutting off the moistened strip. 65
3. In apparatus of the class described, a tank, a moistening device therebelow having an exterior fibrous covering, and a sponge located in said moistening device, rods over which the strip to be moistened is drawn, and 70 means for cutting off the moistened strip.
4. In apparatus of the class described, a tank having means such as a needle-valve to control the outflow of water therefrom, a non-rotatable moistening device therebelow 75 presenting a series of perforations in its body, and an exterior textile cover.

In testimony whereof I have signed my name to this specification in the presence of two subscribing witnesses.

REUBEN H. CHASE.
